UNITED STATES PATENT OFFICE.

THOMAS E. DUCKWORTH, OF COLFAX, LOUISIANA.

WHEELED SCOOP.

1,308,666.

Specification of Letters Patent. Patented July 1, 1919.

Application filed April 8, 1919. Serial No. 288,539.

To all whom it may concern:

Be it known that I, THOMAS E. DUCKWORTH, a citizen of the United States, residing at Colfax, in the county of Grant and State of Louisiana, have invented certain new and useful Improvements in Wheeled Scoops, of which the following is a specification.

The invention provides a scoop for general use which is mounted upon wheels for convenience of movement and operation, the object being to provide novel means for mounting the scoop and unique actuating means, whereby the scoop may be raised and lowered to facilitate loading and unloading thereof.

The drawing illustrates a preferred embodiment of the invention. However, it is to be understood that in adapting the same to meet different conditions, various changes in the form, proportion, and minor details of construction may be resorted to without departing from the nature of the invention as claimed hereinafter.

25 In the drawing hereto attached,

Figure 1 is a side view of a wheeled scoop embodying the invention, the full lines showing the scoop in lowered position and the dotted lines indicating the position of the scoop when raised.

Fig. 2 is a plan view and

Fig. 3 is a detail view showing the position of the operating lever when the scoop is elevated and the lever made secure.

35 Corresponding and like parts are referred to in the following description and indicated in the several views of the drawing by like reference characters.

The scoop 1 is of ordinary formation and 40 comprises a bottom, a back and side. In the preferable construction the scoop is formed of sheet metal of suitable gage depending upon the character of work for which the scoop is designed.

45 An axle 2 is supported in the sides of the scoop and is provided at its ends with crank arms 3 which receive ground wheels 4. The crank arms 3 admit of the raising and lowering of the scoop, as indicated by

50 the dotted and full lines in Fig. 1. A segment 5 is secured to the axle 2 and a suitable connection co-operates with the segment 5 and an operating lever 6 to admit of the scoop being raised or lowered. As shown the 55 connection comprises a rod 7 and a chain 8, the latter passing about the segment 5 and

secured to one end thereof. The operating lever 6 is pivotally supported at 9 to handle bars 10 which are connected to the body of the scoop. A catch 11 near the free end of the lever 6 is adapted to engage a pin 12 and hold the lever in the plane of the handle bars and the scoop in elevated position. When the lever 6 is in upright position, as indicated by the full lines in Fig. 1 the scoop is lowered thereby facilitating the loading or unloading thereof. When the lever 6 is in lowered position, as indicated by the dotted lines in Fig. 1 and the full lines in Fig. 3 the scoop is in elevated position, thereby admitting of the trundling of the same from one place to another.

The handle bars 10 have their middle portions brought close together and their forward portions 13 bent laterally in opposite direction to extend along the back of the scoop and their extremities bent forwardly to engage the sides of the scoop at their rear ends, the laterally bent ends 13 of the handle bars being secured to the scoop in any substantial way. The rear ends 14 of the handle bars are bent laterally to form grips for convenience of manipulating the device. The pin or like part 12 connects the handle bars near their rear ends.

When it is required to load or unload the scoop, the same is lowered by moving the operating lever 6 into upright position. When trundling the scoop the latter is elevated by lowering the lever 6, whereby the scoop may clear objects so as to pass freely over the surface.

A projection 15 at one side of the scoop constitutes a stop to engage the contiguous crank arm 3 to limit the movement of the scoop in one direction when operating the lever 6 to elevate the scoop.

The foregoing description and the drawing have reference to what may be considered the preferred, or approved form of my invention. It is to be understood that I may make such changes in construction and arrangement and combination of parts, materials, dimensions, et cetera, as may prove expedient and fall within the scope 105 of the appended claims.

Having thus fully described my invention, what I claim as new and desire to secure by Letters Patent is:

1. In combination, a scoop, a handle bar 110 projecting rearwardly from the scoop, an axle supporting the scoop and provided at

its ends with crank arms, wheels mounted upon the crank arms, an operating lever mounted upon the handle bar and connecting means between the operating lever and the axle to effect a turning of the latter about the crank arms to raise or lower the scoop.

2. In combination, a scoop, handle bars extending rearwardly from the scoop and 10 transversely spaced, a connecting element joining the rear ends of the handle bars, an axle having the scoop mounted thereon and provided with crank arms, wheels mounted upon the crank arms, an operating lever 15 pivotally mounted between the handle bars, a catch carried by the operating lever to engage the element connecting the rear ends of the handle bars and connecting means between the operating lever and axle.
- 20 3. In combination, a scoop, handle bars

having their end portions extending laterally to form grips and attaching means, respectively, an element connecting the rear ends of the handle bars, an axle receiving the scoop and provided at its ends with 25 crank arms, wheels mounted upon the crank arms, a segment secured to the axle, an operating lever pivotally mounted between the handle bars, connecting means between the operating lever and segment, a catch on 30 the operating lever to engage the element connecting the rear ends of the handle bars and a stop at one side of the scoop for engaging one of the crank arms.

In testimony whereof I affix my signature 35 in presence of two witnesses.

THOMAS E. DUCKWORTH.
